NIGHT LIGHT FIXTURE

Elmer A. Barto, Emmaus, Pa., assignor to Rodale Manufacturing Company, Inc., Emmaus, Pa., a corporation of Pennsylvania

Filed Mar. 4, 1958, Ser. No. 49,899

Term of patent 14 years

(Cl. D48—20)

Fig. 1 is a rear perspective view of a night light fixture and switch embodying my design.

Fig. 2 is a front perspective view thereof showing a bulb in broken lines for illustrative purposes only.

Fig. 3 is a side perspective view thereof.

Fig. 4 is a front elevational view thereof on a reduced scale.

I claim:

The ornamental design for a night light fixture, substantially as shown and described.
